208,825

DISPENSING BOTTLE

Fred E. Hutton, Santa Monica, Calif., assignor to James U. Stewart, La Habra, Calif.

Filed June 7, 1966, Ser. No. 2,593

Term of patent 14 years

(Cl. D58—6)

FIG. 1 is an isometric view of a dispensing bottle showing my new design;

FIG. 2 is a side elevational view, the opposite side being a mirror image of the side shown;

FIG. 3 is a front elevational view;

FIG. 4 is a rear elevational view;

FIG. 5 is a bottom plan view; and

FIG. 6 is a top plan view thereof.

I claim:

The ornamental design for a dispensing bottle, substantially as shown and described.

References Cited

UNITED STATES PATENTS

D. 108,224	2/1938	Spielman	-----	D58—8
D. 143,837	2/1946	Lewis	-----	D58—9
D. 201,215	5/1965	Platte	-----	D58—6
D. 202,302	9/1965	Long	-----	D58—26

OTHER REFERENCES

Mademoiselle, December 1965, page 34, "dressmaker" perfume bottle, lower left corner.

EDWIN H. HUNTER, Primary Examiner.

ROBERT C. SPANGLER, Examiner.